UNITED STATES PATENT OFFICE.

WILBUR F. DAY, OF ST. PAUL, MINNESOTA.

BURNER.

1,130,070.

Specification of Letters Patent.

Patented Mar. 2, 1915.

Application filed May 11, 1914. Serial No. 837,944.

REISSUED

To all whom it may concern:

Be it known that I, WILBUR F. DAY, a citizen of the United States, residing at St. Paul, in the county of Ramsey and State of Minnesota, have invented certain new and useful Improvements in Burners, of which the following is a specification.

My invention relates to improvements in oil burners adapted to be used in connection with the ordinary construction of wood stoves and ranges, and consists particularly in improved features for better distributing fuel to the burners and the heat from the burners than in the ordinary constructions.

In the accompanying drawings forming part of this specification, Figure 1 is a perspective view of my improved invention shown in position in the fire box of a stove; Fig. 2 is a section on line α — α of Fig. 4; Fig. 3 is a plan view of a modification of my construction; Fig. 4 is an elevation of a range broken away and showing a modification of my construction inside; and Fig. 5 is a sectional view of a feed pipe for the fluid.

Referring to the drawings B represents the fire box of an ordinary stove or range and C the grate bars thereof.

A represents the supporting base of my device formed with upwardly and forwardly extending conduits 2, the base plate being formed with openings 3 forming the inlets of said conduits.

My device may be supported in the fire box as by means of the supporting box shown in Fig. 2 formed with vertical sides 4 to form a rest for the base, said supporting sides being carried by a horizontal plate 5 adapted to be embedded in the ashes, said plate being formed with air openings 6.

Having vertically adjustable support upon the front of the base plate through the medium of bolts 7 and slots 8 are the upwardly extending spreader standards 9 carrying at their upper ends inwardly projecting spreaders 10. As shown clearly in Figs. 1 and 2 the spreaders are supported in position facing the outlets of the conduits, and the faces 11 of the spreaders are cut at an angle with the outlet ends of the conduits to throw the flame past the conduits and bring about the more direct and efficient heating of the oven. Of course, it will be apparent that the device may be positioned in the oven so as to face the spreaders either

forwardly or rearwardly to directly heat the oven back or a front water jacket, as the case may be.

Slidably extending through the conduits 60 is a burner tube 12 having its free end closed by a cap 13 and its other end connected by an elbow 23 to a generator tube 14 extending longitudinally of the fire box, the opposite end of the generator tube being 65 connected by an elbow 15 with a tube 16 extending back through the fire box to the inlet tube 17 connected by a supply tube 18 with a source of supply 19. As will be evident by referring to the drawings, the incline of the spreader faces heretofore referred to will be efficient in the maximum degree in directing the flame against the generator tube.

For the purpose of assisting in regulating the inlet flow of the oil as well as the heat retention qualities of the pipe 16 I arrange in the pipe 16 coiled wires 20. I also preferably fill the inlet tube 17 with gravel 21 or other suitable material to control the 70 pressure and flow of fluid.

In Figs. 1 and 2 I show the pipe 14 left out with the pipe 12 connected by an elbow directly with the pipe 16. Either arrangement of pipe, where desired, may be used 85 without departing from the idea of my invention. A suitable controlling valve 22 is employed in connection with the inlet pipe. The tube 12 extending through the conduits is formed with burner jet openings, which 90 by the sliding of the pipes may be caused to stand either inside the conduits or outside.

In use the supporting base 5 will stand embedded in the ashes. When it is desired to start the burner the pipes will be withdrawn sufficiently to position the burner jets outside the conduits. The controlling valve then being opened, the oil will flow through the tubing and pass through the jet openings upon the ashes outside the conduits. The 100 valve then being closed and the oil upon the ashes lighted the resulting flame will heat the tubing. When the parts are sufficiently heated the pipe will be moved back to bring the jet openings within the conduits, and the inlet valve then being opened the oil as it passes through the heated tubes will be generated into gas, issuing in the form of gas from the jet openings. The gas from the jet openings passing through the outlet 110 openings from the conduits will strike the spreaders and will be directed by the
